UNITED STATES PATENT OFFICE

HELMAN E. EICHNER, OF PALMYRA, NEW JERSEY

STRUCTURAL MEMBER

Application filed March 30, 1929. Serial No. 351,419.

My invention relates to walls and floors and to structural members for use in walls and floors, either or both.

A purpose of my invention is to provide 5 all-metal composite structural members such as wall studs, floor joists, beams and the like that present, each of them, one or more strip surfaces along which the member is adapted to be effectively nailed.

10 A further purpose is to include strips of resilient metal filler adapted to receive and effectively hold nails between metal side members adapted to give the composite member the desired stiffness, strength and outside 15 structural dimensions.

A further purpose is to provide a desirable form of all-metal filler for use between side members of composite studs, floor joists, beams or the like.

20 A further purpose is to make an all-metal composite stud or the like present a strip nailing surface of considerable width along one or more of its sides.

A further purpose is to make structural 25 members for walls and floors or the like such as studs and joists present toward one another intermediate their width along their length lateral projections for seating and supporting opposite sides of a sheet of insulation material to be placed intermediate 30 the wall surfaces upon opposite sides of the studs or floor and ceiling surfaces upon opposite sides of joist in order to make the wall or floor more resistant to the passage of heat 35 and sound.

A further purpose is to make structural studs and joists and the like with perforations at each end and preferably at spaced intervals along their lengths for adaptation 40 to pass piping and electric conduits.

A further purpose is to clamp structural side members upon intermediate metal nailing filler material by flap portions of the side members bent inwardly from one member to 45 pass through a suitable perforation in the

other member and clinched upon the other member.

A further purpose is to provide a form of composite studs that are particularly well adapted to use in holding forms for concrete 50 walls, the studs being left in place after the walls have been formed while the intermediate wall portions of the forms are removed for use elsewhere.

A further purpose is to provide a desirable 55 form of thin back plastered partition.

Further purposes will appear in the specification and in the claims.

I have elected to illustrate a few only of the different forms of my invention, selecting 60 forms that are practical and efficient in operation and which well illustrate the principles involved.

Figure 1 is a fragmentary broken horizontal section through a portion of dwelling 65 structure embodying different features of my invention, the view being to considerable extent diagrammatic and showing at one portion stud members at different stages of the building operation.

Figure 2 is a fragmentary broken vertical 70 sectional view of structure shown in Figure 1.

Figure 3 is an enlarged fragment corresponding to a portion of Figure 1 but showing a different form of all-metal furring strip 75 from that shown in Figure 1.

Figure 4 is an enlarged fragment of Figure 2.

Figures 5 and 6 are sectional views through 80 slightly different forms of all-metal filler for use between structural members to afford nailing surface upon the sides of these members.

Figure 7 is a side view of structure shown 85 in Figure 6.

Figures 8 and 9 are sectional views illustrating slightly different forms of metallic filler adapted to receive and hold nails.

Figure 10 is a fragmentary perspective 90

view showing a composite stud embodying one form of one feature of my invention.

Figure 11 is a horizontal section through a wall adjacent a window showing a desirable composite stud structure for use at a window.

Figure 12 is a fragmentary section through a wall showing another composite stud member for use at joints between metal lath and provided with spaced strip surfaces for the adjoining sides of adjacent metal lath.

Figure 13 is a view to reduced scale through a wall adjacent a window and shows the application of the three forms of studs illustrated in Figures 10, 11 and 12.

Figure 14 is an enlarged fragment of Figure 2.

Figure 15 is an enlarged fragment of Figure 1.

Figure 16 is a fragmentary section taken upon the line 16—16 of Figure 15.

Figure 17 is a fragmentary vertical section taken upon the line 17—17 of Figure 14.

Like numerals refer to like parts in all figures.

Describing in illustration and not in limitation and referring to the drawings:—

My invention is directed to providing desirable forms of inexpensive fireproof floor and wall structures with particular adaptation to use in dwelling houses, and is also directed to providing all-metal composite building members such as studding, floor joists and beams that will be wholly fireproof, that will present comparatively wide nailing surfaces along their lengths and that will be easy and inexpensive to manufacture.

One of the important detail features of my invention is directed to the form of all-metal filler which I insert between the side pieces of my composite studs, beams, joists or the like.

Another detail feature is directed to the method of placing the furring studs along a concrete wall, initially using the studs as a permanent portion of a form for use when making the wall, which after the non-permanent portions of the form are lifted away presents the projecting fireproof furring studs in position to receive the metal lath or the like of the inner wall, the all-metal studs presenting outwardly relatively wide nailing surfaces along their lengths.

Still other advantageous detail features include forming the composite studs, floor joists and the like so that they have an easy adaptation to pass water and gas piping and electric conduits; and in providing a novel connection between walls and floors that makes it very easy to install and to effectively support the floor joists.

The side pieces for my all-metal composite structural frame members are made light or heavy and of variant sectional contour ac-

cording to circumstance and their service duties.

When my all-metal composite members are to serve as wall studs or furring strips I prefer to make the side pieces of each composite member of fairly light sheet metal, rolled or pressed cold to form, while if the composite members are to stand heavy duty such as is normally the case when the members are to be used as floor joists or beams I prefer to make the side pieces of each member of hot rolled channels or the like.

In either case I usually prefer to provide the side pieces with longitudinal laterally outwardly projecting beads or flanges intermediate the widths of the side pieces.

These projections or flanges on each piece are adapted to seat one side of an insulation sheet placed between successive composite studs or joists intermediate the widths of the composite member.

I insert these intermediate sheets for purposes of heat and sound insulation, either or both.

In Figures 1 and 2 I show a fragmentary portion of a dwelling frame structure in which are embodied a number of the different advantageous features of my invention.

The inside of an outside concrete wall 20, is shown furred by the vertical furring strips 21 which may be all alike and constructed as composite members like the stud 22 of Figure 15.

The composite furring studs comprise strengthening and stiffening side pieces 24 and 25, a nailing filler 26 compressed between the side pieces and ties fastening the side pieces together upon the compressed filler.

The filler material intermediate the side pieces is preferably of considerable thickness so that the nailing surfaces presented along opposing faces of the composite studs are of considerable width.

The side pieces 24 and 25 are desirably usually counterpart cold rolled sheet metal channels held together upon the intermediate filler in any suitable way.

The application of the furring strips as a permanent part of the inside wall of the form for use in making the concrete wall is illustrated in Figure 1 at the studs 27.

The studs, as shown at 27 are set up with the nails or spikes 28 projecting into the space that is to be occupied by the concrete wall and are fastened in any suitable way, not shown, in the position they are to finally occupy.

Portions of the form wall intermediate the studs are shown as comprising boards 29 which are placed to overlap the inside flanges of the successive studs and are held from moving outwardly by suitable fastening members 30 blocking the space between the boards 29 and the overlapping outside flanges 31 of the respective studs. The fastening blocks

30 conveniently comprise narrow wooden cleats loosely nailed to the boards 29.

The outside wall of the form has not been shown in that it may be made in any suitable and usual way.

After the concrete has been poured and has suitably hardened the fastening cleats 30 are taken out after which the board portions 29 of the form lift away leaving the studs with 10 the projecting nails embedded in the concrete.

The furring studs may carry intermediate their inside and outside faces sheets 32 of heat and sound insulating material and at 15 their inside faces receive metal lath 33 which is nailed to place, the nails being received and held by the compressed openwork filler intermediate the side pieces of each stud.

At each floor level in the wall along the 20 ends of the floor joists I place a horizontal T member 35 preferably a composite member.

I place the body portion of the T intermediate the studs on portions of the building respectively above and below the floor so that 25 the body portion 36 of the T member provides a cap for the top ends of the lower studs and a base for the bottom ends of the upper studs, preferably placing the upper and lower studs in line and using common 30 bolts or rivets 37 to fasten the bottom flanges 38 of the upper studs and top flanges 39 of the lower studs together upon the body portion 36 of the T member.

I place the cross portion 40 of the T, which 35 preferably has a width substantially the same as the depth of the floor joists, vertical and in position to receive the ends of the floor joists and fasten the floor joists to this vertical portion of the T in any suitable way, 40 preferably by rivets or bolts 41.

I prefer to make the T member composite so that it comprises upper and lower angles 42 and 43 having flat portions, face to face to form the body of the T and the side portions extending respectively upwardly and 45 downwardly to form the cross portion of the T.

Desirably I provide an outwardly directed flange 44 along the bottom of the cross portion 50 of the T.

This flange receives and supports the ends of the floor joists 45 making it very easy to erect the joists and if desired, the bottom flanges 46 of the floor joists may be fastened 55 at 47 to this inwardly extending flange of the T member.

When the T member 35 is made of two angles, the bottom angle becomes of Z contour if the bottom of the cross portion of the 60 T is flanged at 44 to support the inner ends of the floor joists.

Plaster 34 is shown covering the metal lath.

The cross portion 40 of the T member, preferably comprising the upwardly and downwardly extending sides of upper and lower 65

angles has a total vertical width about equal to the depth of the floor joists 45.

The ends of the joists abut against the vertical face of the T member to which they are preferably bolted or riveted through laterally 70 extending end flanges 48 of the joists.

One of the important detail features of my invention covers the use of an all-metal structural member comprising stiffening and strengthening side pieces and intermediate 75 openwork resilient filler compressed between the side pieces, preferably of considerable width, and adapted to receive and hold nails.

In view of the fact that the filler may be of different forms any one of which may be preferable under certain conditions, I have shown the filler conventionally in the different composite structural members, and have illustrated in Figures 5 to 9 a few of the many different forms of filler that may be used.

Broadly the filler comprises an openwork metallic structure adapted to be resiliently compressed between suitable side pieces and to present when thus compressed an openwork edge that will receive and hold nails.

In the form of Figures 5 to 7 the filler comprises a succession of metal sheets 49 that present surfaces made up of lateral puncturing distortions extending in one direction interspersed with similar puncturing distortions extending laterally in the opposite direction, the puncturing distortions comprising laterally extending flaps bent alternately in opposite directions.

In Figure 6 the filler material comprises a pile made up exclusively of these distorted sheets while in Figure 5 I show that the sheets having the puncturing distortions may advantageously alternate with flat sheets 50 of equal width, the flat sheets 50 preventing any nesting of the projections of one sheet with the cavities of an adjacent sheet.

In the forms of Figures 5 and 6 metal sheets are deformed by the use of puncturing distortions. These comprise flaps 51 bending laterally in one direction alternating with flaps 52 bending laterally in the other direction, the flaps maintaining connection with the sheet along one side only of the flap, and the puncturing being in the nature of shearings along the fronts and sides of the flaps. The deformations may take many forms.

In Figure 8 I show a form in which the puncturing distortions 53 are interspersed oppositely extending serrations obtained by sending the strips between suitable serrated rolls in which each roll is provided with serrations and cavities that respectively register with corresponding cavities and serrations of the other.

As in Figure 5 the composite filler comprises a pile of sheets in which the strips 54 having the puncturing distortions may desirably alternate with flat strips 50 in order to 125

avoid undue nesting between the serrations and cavities of adjacent sheets.

In the form shown in Figure 9 the filler comprises corrugated sheets 55 that alternate with the flat sheets 50, the corrugated sheets being preferably adjacent the structural side pieces of the composite member and separated from one another by the flat strips.

In all of these forms a nail enters the filler by resiliently straining and distorting an openwork structure that yields resiliently to the forcible entry of the nail and that resiliently grips and holds the nails after they have been driven in.

The filler should preferably have considerable width so that an erecting workman does not need to make any close measuring in order to locate the proper position for nailing and when made as described the composite member is adapted to receive nails almost equally well across the whole width of the filler.

The composite structural members whether studs or joists are preferably provided with longitudinal laterally extending beads or projections 56 for receiving and seating the intermediate sheets 32 of heat and sound insulating material.

These seats may comprise grooves or spaced flanges rolled upon the structural side pieces of the composite members as best seen in Figures 15 and 17, either cold rolled or hot rolled when forming the side pieces.

The sheets 32 of insulation material are pushed to place after the joists or studs have been erected so that the sides of the sheets are received in the opposing grooves presented by the successive structural members, joists or studs, at 57 in Figures 1 and 14 to 17.

The longitudinal seats 56 are shown half way between opposite sides of the studs and joists. In certain cases however it may be preferable to place these seats somewhat to one side of the middle of the space between opposing nailing sides of the studs or joists in order to provide more ample space for piping and conduit along one side of the sheet insulation.

I preferably provide the structural members with perforations 58 in order to more readily pass electric conduits, piping and the like.

I show these perforations at each end of the stud members and also at each end of the joist members and may or may not provide them at spaced intervals intermediate the length of the members.

Both the studs and joists are preferably flanged laterally at the ends immediately adjacent the transverse opening 58 for adaptation to pass the conduits and piping. These flanges are shown at 38 and 39 on the studs and at 48 on the floor joists.

In many cases it may be preferable to cut

the sheet 32 away to give passage to the piping of electrical conduit and it is preferable to install this piping and conduit at the same time that the studs and joists are installed.

The insulation sheets may bend to one side of such pipe or conduit or may be cut away to engage the side of the pipe or conduit as preferred.

I preferably provide the end flanges of the studs and joists with suitable perforations 59 for nails or bolts, either or both according to the preference of the builder.

At the vertical wall corners I place studs 60 and 61 in the two walls adjacent one another at their inner sides and connect the outside portions of these studs together by a suitable angle member 62.

This provides an open passage 63 intermediate the inside faces of the angle 62 and the inside faces of the adjacent stud members 60 and 61 and this passage provides convenient room for piping and electric conduits.

The outwardly presented faces of the composite studs and joists present relatively wide strips that are adapted to receive and hold nails.

I may nail plaster board directly to the under side of the floor joists as indicated at Figure 2 or may nail metal lath to the under side of the floor joists as shown at 65 and then cover the metal lath with plaster 34.

The same is true with respect to the vertical studs which may preferably be covered first with metal lath 33 and then coated with plaster 34 or where desired may receive the plaster board without the lath as indicated at 66, Figures 4 and 16.

Where the partitions are to be very thin I prefer to use composite structural members comprising light angles 67, Figure 1, that are fastened together in any suitable way upon the intermediate openwork metal filler 26.

These angles may have sides of perhaps only three-quarter inch or less. They are set vertical along the desired wall line and on one side receive metal lath 69 which is plastered at 68 upon the outside, the plaster penetrating and covering to a considerable depth the reverse side of the metal lath.

After the plaster hardens the other side of the wall is back plastered at 70 covering the angles 67, and the result is a very satisfactory though very thin wall that is particularly well adapted for use in making closets, booths and the like.

I may widely vary the character of the composite structural members to accommodate different service conditions and show in Figures 11 to 13 two out of the many special forms of composite studs that may be used to advantage.

In Figure 11 I show a special all-metal composite stud member 71 for use adjacent a window. The composite member 71 has a

wall portion 72 that is generally similar to the wall studs 22 already described.

This portion serves as the end wall stud and presents nailing surfaces to receive the 5 metal lath 73 and 74 upon opposite sides of the wall.

On top of the lath are shown the plaster stop members 75 and 76 held to place by nails 77.

10 In order to provide nailing surfaces for the window frame member 78 I extend the outer flanges of one of the channel members at 79 and 80 and insert my openwork all-metal filler between the inner sides of these 15 flanges and plate members 81 and 82, compressing the filler against the flanges by suitable tie members 83 between the flanges and the plates.

Preferably the plaster stop members 75 20 and 76, the window trim members 84 and 85 and the door frame member 78 are all of metal so that the window or door may be wholly fireproof.

The special composite stud member 86 25 shown in Figures 12 and 13 provides spaced nailing surfaces at 87 that make it much more easy to nail up the sheets of metal lath and that stiffen the wall at the joints between the lath which is sometimes desirable.

30 As illustrated in Figures 4 and 16 I may provide the wall frames with base and cap members 88 and 89 respectively.

As illustrated these include all-metal composite members having a generally rectangular sectional contour of width to present nailing surfaces to the metal lath or plaster board along the floor and ceiling respectively intermediate the studs.

These members may be made up wholly of 40 the distorted sheet metal strips used for filler, the sheets being compressed together and perforated vertically to provide nail holes and held together in compressed position by suitable tubular rivets or otherwise, or may include upper and lower plate members and the intermediate strips of compressed filler material as already described, the section being permissibly similar to that of the studs 45 22 except that the flanges extending outwardly from the nailing surfaces are omitted.

My construction is suited to use in various walls whether horizontal or vertical including floors, ceilings and side walls and wherever this meaning can reasonably be given to it 55 "wall" or "walls" is or are to be interpreted in this way in my claims.

It will be evident that my cushioning material permits insertion of nails or screws not only in any angular position within a plane 60 or planes parallel to the faces of the metal between which my filler is secured, but that nails and screws may be driven at an angle to such parallel planes.

It will be further evident that my filler material is not dependent for its success upon

the relation between the curvature of some corrugation and the diameter of a nail or a screw intended to be inserted but that nails and screws of various sizes can be driven within one of my fillers and nails and screws 70 of different sizes can be driven close to each other.

In view of my invention and disclosure variations and modifications to meet individual whim or particular need will doubtless 75 become evident to others skilled in the art, to obtain all or part of the benefits of my invention without copying the structure shown, and I, therefore, claim all such in so far as they fall within the reasonable spirit and 80 scope of my invention.

Having thus described my invention, what I claim as new and desire to secure by Letters Patent is:

1. An all-metal composite structural member including a spaced pair of metal side members, one of them a structural member, openwork resilient metal filler comprising deformed plates of considerable composite thickness compressed between the side members and ties between the side members holding them to position so that they compress the filler, the filler presenting an outwardly directed strip nailing surface of considerable width intermediate the side members. 95

2. An all-metal composite structural member including a spaced pair of metal side members, one of them a structural member, an openwork resilient metal filler comprising deformed and flat plates of considerable composite thickness compressed between the side members and ties between the side members holding them to position so that they compress the filler, the filler presenting an outwardly directed strip nailing surface of considerable width intermediate the side members. 100

3. An all-metal composite structural member including metal side members, one of which is a structural member, a pile of metal sheets compressed together between the side members and ties holding the side members together in position to compress the pile, sheets of the pile having a succession of lateral distortions engaging the adjoining 110 sheets so that the outwardly directed edge of the compressed pile presents an openwork surface adapted to receive and hold nails. 105

4. An all-metal composite structural member including metal side members, a pile of metal sheets compressed between the side members, ties holding the members together against the compressed pile, sheets of the pile having lateral distortions interspersed over their surfaces engaging adjoining flat sheets 120 so that the outwardly directed edge of the pile presents an openwork structure adapted to receive and hold nails. 125

5. An all-metal composite structural member including a pair of structural side mem-

bers, a pile of laterally distorted metal sheets compressed between the side members providing a zone of nail-receiving material between the side members and ties holding the 5 side members to place upon the pile, sheets of the pile having puncturing lateral distortions interspersed over their surfaces engaging an adjacent sheet so that the outwardly directed edge of the pile presents an open- 10 work structure adapted to receive and hold nails.

6. An all-metal composite structural member including structural side members, a pile of laterally distorted metal sheets compressed 15 between the side members and ties holding the side members to place upon the pile, sheets of the pile having each puncturing lateral distortions interspersed over the sheet surface extending toward one of the side 20 members and other puncturing lateral distortions interspersed among the said first distortions extending toward the other side member.

7. An all-metal composite structural member including structural side members, a pile 25 of metal sheets compressed between the side members and ties holding the side members to place upon the pile, alternate sheets of the pile having lateral puncturing distortions interspersed over their surfaces, lateral distortions toward one side being interspersed with 30 lateral distortions toward the other side, so that the outwardly directed edge of the compressed pile presents an openwork structure 35 adapted to receive and hold nails.

8. A composite all-metal structural member including a stud for the framework of a wall and including side pieces to present their edges to the inner side of a wall, a compressed 40 all-metal resilient metal openwork filler intermediate the side pieces along the edges thereof that are to lie adjacent the wall and ties fastening the side pieces to place against the filler, the outwardly directed surfaces of 45 the filler presenting across and along the outer surface a succession of layers of inwardly directed passages, said passages being adapted to receive nails by a resilient distortion of the filler.

50 9. A filler material for insertion between stiffening structural members comprising a succession of plates, each having lateral puncturing distortions interspersed over its surface in opposite directions, the lateral discontinuous puncturing distortions in one direction being interspersed between the lateral puncturing distortions in the other direction.

55 10. A filler material for insertion between stiffening structural members comprising lateral puncturing distortions interspersed over its surface that includes discontinuous puncturing distortions in two directions, the puncturing distortions in one direction being 60 interspersed with those in the other direction.

and substantially plane plates intermediate the punctured distorted plates.

11. In a composite wall spaced angles having parallel sides of the angles, filler material of openwork metal between the sides 70 and a tie fastening the angles providing a plurality of parallel planes of nail-receiving capability upon the filler material.

12. An all-metal composite structural member adapted to receive and hold nails 75 along opposite sides and comprising side members presenting edges along the planes of the nailing faces and resilient openwork metal filler presenting many planes of nail-receiving resilient material compressed between the side members and ties fastening the side members together against the filler, said ties comprising integral portions of one or both of the side pieces.

13. A composite structural stud member 80 for use at a transversely finished end of a partition wall comprising outer and inner vertically extending metal side members presenting their widths transversely across the thickness of the wall, filler material compressed between the side members, tie members holding the side members together upon the filler material so that the filler material 85 presents nailing surfaces upon opposite sides of the width of the composite stud member, flanges extending from the outer structural member toward the wall end on opposite sides 90 of the width of said outer member, expanded filler material upon the inside faces of the flanges and metal means clamping the filler 95 material to place so that the filler material presents nailing surfaces transverse to the wall for nailing an end finishing member to the composite stud member at the end of the 100 wall.

14. A composite structural stud member for use in a partition wall and comprising vertically extending structural members presenting their widths transversely across the thickness of the wall, channel members intermediate the structural members, one at each side of the composite member intermediate the side members, openwork metal filler intermediate the channels and the side members and means tying the members together 110 upon the filler so that the filler presents nailing surfaces at opposite sides of the channel adjacent the side members upon each side of the composite member.

115 15. A metal composite structural member including a spaced pair of metal side members, resilient metal filler comprising many layers of alternating plain and resilient corrugated material held between the side members and ties between the side members holding them in position relatively to each other, the filler presenting an outward nail-receiving surface.

120 16. A composite structural member comprising side metal members and an intermedi- 130

ate filler exposed at the edge of the side members and made up of substantially parallelly plates having projections between the plates and providing a zone of parallel spaces between the plates all of which spaces are
5 adapted to receive and hold nails.

17. A receiving strip for nails comprising a plurality of spaced flat plates resilient corrugated metal sheets between the plates and
10 on opposite sides of intervening plates and side supporting means for clamping the plates together to expose an edge zone for nailing purposes providing a plurality of parallel nailing paths.
